Specification of Letters Patent. Patented July 21, 1914.

Original application filed February 27, 1908, Serial No. 418,008. Divided and this application filed March 28, 1912. Serial No. 686,919.

To all whom it may concern:

Be it known that I, ELMER P. NICHOLS, a citizen of the United States, and resident of Manchester, in the county of Hillsboro and 5 State of New Hampshire, have invented an Improvement in Machines for Grade-Marking Died-Out Leather Pieces, of which the following description, in connection with the accompanying drawings, is a specification, 10 like letters on the drawings representing like parts.

My present invention relates to evening and grading machines, whose purpose, use and general construction are set forth at 15 length in my Reissue Patent No. 12,288 and later Patents Nos. 841,809, 1,009,988, and 1,046,213, this application being a division of my application Serial No. 418,008, filed February 27, 1908, now Patent No. 1,057,358, 20 and being restricted to the grade-marking features of the invention, whose broader claims, specific claims to the evening mechanism, and combination claims which involve both the evening and marking mechanisms 25 are contained in the parent case. Accordingly I refer to the parent case for the more extended description of the machine in general and the various advantages of the invention in operation, construction and results, 30 and restrict the present application more particularly to those divisional features which form the subjects matter of the claims.

In the drawings, Figure 1 is a central, longitudinal vertical sectional view of the 35 machine; Figs. 2 and 3 are vertical cross-sectional views taken respectively on the lines 2—2 and 3—3 Fig. 1; Fig. 4 is a right-hand side elevation of the machine; Fig. 5 is a left-hand side elevation of the machine; 40 Fig. 5^a is a fragmentary front elevation of the clutch mechanism; and Fig. 6 is a top plan view of the machine.

The machine in general consists of much the same parts and general organization as 45 my above mentioned patents, particularly the last mentioned, said parts, however, being arranged and coördinated quite differently. Mounted in the frame 1 at the in-going end of the machine are upper and 50 lower feed rolls 2, 3, the latter constituting a feeler roll or leather-detecting device, (for detecting thin spots, i. e. portions or places sufficiently thinner than an adjacent place of

the stock to permit relative movement of the rolls 2, 3 toward each other at that spot) 55 and being mounted in vertical movable bearings 4 at its opposite ends guided in ways 5 in the frame, and the former roll 2 having its journal bearings 6 normally stationary or fixed but adjustable at its opposite ends by 60 any suitable means, as by threaded bolts 7, 8, free to rotate, but immovable lengthwise, in a frame head 9, said adjusting bolts having worm ends 10 at their upper ends engaged by worms 11 fast on the opposite ends 65 of a transverse shaft 12 made angular to be readily grasped for turning by hand. The top roll 2 is preferably plain or smooth, and the bottom roll slightly corrugated or scored. The vertically movable roll 3 which constitutes the main feeler-device or engaging portion of the feeler mechanism is connected by 70 any suitable means to the transmitting mechanism for transmitting the varying thicknesses detected by the feeler mechanism, 75 said means being herein shown, and preferably consisting of, a bridge or yoke 13 bolted at its opposite ends to the adjacent journal bearings 4 of the roll and normally held upward by a heavy central equalizer spring 14, 80 capable of delicate adjustment by means of a bolt 15 operating through a fixed portion 16 of the main frame of the machine, whereby the roll 3 may be given exactly the right pressure, and no more, necessary for accomplishing the most effective thickness-detecting 85 results.

The feeler mechanism is arranged to engage the flesh side or under side of the piece of stock, which is always the side containing 90 the unevennesses of the leather, and the marking mechanism is arranged to operate on the upper or skin side of the stock; and in connection with the feeler mechanism I provide an equalizer spring 14 located centrally for maintaining the feeler roll 3 in 95 perfect balance as it engages the stock, said centrally mounted spring 14 being independent of all the rest of the mechanism, i. e. it is mounted directly on the frame of the machine and transmits its pressure directly to the roll 3, and therefore does not bring any strains or wear upon any portion of the train 100 of transmitting mechanism. The latter consists of depending feeler-posts or detector rods 17, 18 having heads 19 delicately ad-

justable by nuts 20 on the ends of said posts, said posts passing through slots or holes 21 in a relatively heavy transmission lever 22, herein shown as pivotally mounted at 23 in the frame of the machine, apertured at 24 for the unrestricted passage of the spring 14 and provided at its free end, see Fig. 1, with a pivoted depending arm 26 slotted at 27 and normally engaging at the upper end of said slot a pin 28 of a rocker arm 29 fast on a shaft 30 journaled to freely rotate in the frame of the machine. A spring 228 tends always to hold the arm or crank 29 upward so that its pin 28 occupies the upper end of the slot 27 of the arm 26. Fast on said shaft 30 is a wheel 31 and pinion, or rather sector, 32, the former constituting part of the locking means for locking the gage adjuster mechanism and the latter engaging a rack 33 whose opposite end 34 serves to rotate a pinion 35 which operates the die or grade-marking mechanism and sets the skiving mechanism.

The pinion 35 is fast on a shaft 36 provided with a pinion 37 engaging a rack bar 38 provided with wedges or inclines 39 cooperating with opposite inclines or wedges 40 on the upper sides of the journal boxes 41 of the gage roll or pressure device 42 and acting as stop-means for positively limiting the upward movement of said pressure device 42. A spring 43 connected at one end to the bar 38 and at the other end to a stationary post prevents back play. The marking roll or die 44 carries a pinion 45 in mesh with a toothed sector 46 mounted to swing from a pivot 47 in the cross bar 48 of the head 49 which carries the marking die or roll, said toothed sector being swung by an arm 50 pivoted at 51 to the outer end of the rack 38, and said head 49 raised by a cam 52 engaging a plunger 53 depending from the cross bar 48, which is held under constant downward tendency by springs 54. This mechanism, however, as just described, has proved in practice liable to error, as the necessarily sudden movements due to the rapid passing of a piece of stock in engagement with the feeler mechanism has caused the swinging sector 46 and rotary die 44 to tend to vibrate or chatter and rebound more or less, so that it has been liable to make false marks, and accordingly I have succeeded in entirely preventing this uncertainty and liability to error, and yet without decreasing the speed of the machine and the rapidity of its execution, simply by introducing an oil check or friction retarding device 55. Any of the well known friction retarding devices may be employed for this purpose, my invention, so far as this detail is concerned, not residing in the kind of friction device employed, but in providing means for insuring that notwithstanding the suddenness of positive

movement and the resulting momentum of the swinging and rotating parts of the marking mechanism, the latter shall stop precisely at the point corresponding to the determination of the feeler mechanism and shall be accurate, definite and certain notwithstanding the delicacy and exceedingly small differences of thickness determined and marked. The oil check 55 consists of a closed cylinder 56 containing a piston 57 and piston rod 58 whose upper end is pivoted at 59 to the sector 32. A quarter-iron, half-iron, and in fact even a whole iron or still coarser measurement of leather is nevertheless such a slight difference in thickness (an iron being one forty-eighth of an inch) that, in order clearly to stamp the successive grade marks distinctly from each other on the leather pieces I have constructed the grade-marking mechanism so as to amplify the movement of the marker to such an extent that, notwithstanding the exceedingly slight movement at the feeler mechanism end of the machine, the grade marker will be compelled to move for each increment of measurement a sufficiently great distance to make certain that the correct mark and no other will be imparted to the leather and not a portion of two marks or possibly of three marks, and this taken in connection with the practical necessity of running my machine at high speed in order to accomplish the work which is required of it according to the usual shoe factory practice, and the necessarily strong and therefore somewhat heavy construction of the movable parts, originally made it exceedingly difficult to obtain accuracy of marking, as incorrectness would result at times in apparently inexplicable ways, which proved practically insurmountable until I discovered that these errors were due, not to incorrectness of mechanism, but mainly to the give or yield and spring of the metal under the exceedingly sudden starting and stopping movements to which the moving parts are subjected in the practical running of the machine. I make this explanation because I wish it understood that my invention does not reside in providing a dash pot as such, but in discovering the cause of the previous uncertainties and errors in the grade-marking results of the machine, and in discovering that said uncertainties and errors could be entirely eliminated simply by interposing a strong friction device in the train of transmission mechanism adjacent the grading end of the machine, operating to absorb and take up the sudden shock and thereby prevent transmitting it to the marking wheel. As the ratchet wheel 31 is suddenly moved forward contra-clockwise by its pull in response to the changing position of the feeler mechanism, the shaft 30 and sector 32 are given a corresponding sudden impulse which is

received and held against modification by the firm frictional resistance of the friction device 55-58 so that, notwithstanding the momentum of the swinging sector 46, rotary 5 marking wheel or die 44, and the return influence of the spring 43 and influence of the spring 127, etc., the various parts of the grading mechanism simply move forward the exact distance required by said forward 10 movement of the ratchet wheel 31 and not the slightest distance more, so that when the marking die or wheel is tripped, the required die number is in truly vertical position and not an adjacent improper die number, and what is of still greater consequence, 15 the die wheel is still and not imperceptibly chattering or trembling with a rotary vibration as before.

The lower roll 60 which serves to hold up 20 the stock against the gage roll 42 to be skived by the skiving knife 61 is also mounted in sliding bearings 62 and is yieldingly supported as in my previous machine, but instead of being supported by springs located at the ends of the roll under the journal bearings thereof, I secure to said journal bearings a yoke 63 which extends beneath the roll 60, and mount the supporting 25 springs 65 much closer together than before, as clearly shown in Fig. 3, said springs engaging said yoke as nearly as practicable beneath the path where the edges of the work will pass when traveling between the two rolls, the lower ends of the springs being supported adjustably in any suitable 30 manner, as by bolts 66 adjustable in a cross bar 67 fast on the frame of the machine, and the opposite ends of the yoke and hence of the roll 60 being adjustably limited in their 35 upward movement by bolts or links 68 passing through said cross bar, beneath which are nuts 69. By having the springs 65 thus located under the work, they always keep the roll against the stock even though the 40 variations in relative thickness between the opposite edges of the stock should be extreme. As the gage roll 42 is freely movable within the limits set by the limiting wedges or inclines, it applies a uniform pressure 45 to the leather and accomplishes the various additional functions of operating the gate, tripping the marking portion of the grading mechanism, and preventing the accidental escape of stock from the machine 50 without being graded in some way. To prevent the skivings following the roll 60 I have provided grooves 70 in the roll 60, in which stripping fingers 71 extend from the rear face of the yoke 63 to which they are 55 clamped by a bar 72.

Referring again to the grade-marking mechanism, the cam 52 is positively rotated by a train of gears 73, 74, 75, 76, the latter being in the form of a spring clutch normally impelled by its spring 77 to engage

the clutch end 78 of a pinion 79 directly driven by the main shaft 80, said clutch gear 76 being normally restrained by a pivoted cam plate or combined stop and restraining device 81 held by a spring 82, all as in my copending Patent No. 1,009,988 (although herein claimed), but in the machine of my said patent, I have found in practice that there is a tendency of the die to repeat its grade marking on the same piece of stock, 70 due to the failure of the cam plate 81 to retract the clutch gear 76 at the proper moment, and accordingly in my present machine I have arranged a different mechanism for effectually stopping or preventing the 75 die from improperly repeating its grading. The cam plate 81 has a forward portion 83 in which slides a latch 84 normally held downward by a spring 85 in position to be engaged by a dog 86 pivoted at 87 to the 80 frame and actuated by a link 88 extending upward from a bar 89 pivoted at 90 to the side of the frame and connected at 91 to a rod 92 having a strap 93 around the journal end of the upper roll 42. The latch 84 is 85 outwardly bent at its upper end 95 to overhang the projecting end or finger 96 of a lever 97 pivoted at 98 and extending in position to be tripped by a pin 99 projecting from the pinion 73 which operates the die-actuating cam 52. By this mechanism, whenever the gage roll 42 is raised by the passage of a piece of stock, the dog 86 instantly swings the cam plate 81 out of restraining engagement with the radially projecting roll α of the clutch gear 76, thereby 90 permitting the spring 77 to throw in the clutch and hence permitting the train of gears 76, 75, 74, 73 to actuate the marking die for one marking, but as the gear 73 95 makes one revolution, as required for said one marking, its stop pin 99 causes the stop lever 97 to raise the latch 84 out of engagement with the dog 86, with the result that 100 instantly the cam plate or stop device 81 is retracted by its spring 82, and thereby the marking mechanism is absolutely stopped. When the cam plate is retracted, its inclined face or edge engages the radial roll α of the 105 sliding rotary clutch member 76, which engagement instantly draws said member to the right, Fig. 5^a, to inoperative position so that the die wheel 44 cannot operate a second time for the same piece of stock.

The bar 89 is normally counterbalanced by a spring 100 and its forward end carries a pivoted lifting rod 101 normally held forward by a spring 102 in lifting engagement beneath a crank 103 for holding the gate 104 raised or open which controls the feeding of the stock to the machine. Thus said gate is lifted to permit the entrance of a fresh piece of stock each time that the graded piece of stock passes from beneath the roll 42 the previous raising of the roll 105 110 115 120 125 130

42 by the outgoing stock having rocked lever 89 so as to lower rod 101 whose spring 102 has thereupon pulled the rod 101 forward beneath the end of crank 103, ready 5 for said lifting operation. The gate is caused to fall each time that a piece of stock enters between the feeding rolls 2, 3, by the retraction or moving backward of the lifting rod 101 by the engagement with its upper end of a pin 103 projecting from an 10 arm 106 extending upward from the transmission lever 22, it being remembered that the latter is depressed each time a piece of stock enters the machine and moves downward the roll 3 and feeler posts or detector rods 17, 18 away from the roll 2.

15 In front of the gate I have placed a longer feed table than before, as herein indicated at 107, and have provided opposite 20 length guides 108 simultaneously adjusted toward and from each other by a right and left threaded screw 109 in order that the stock may always be entered straight into the machine and all the pieces in the same 25 path. By this means uniformity of grading with relation to the edges of the stock is secured by passing the edges of successive pieces always over the feeler mechanism in precisely the same relation to the center 30 thereof.

35 In my before mentioned patent, means for centering the stock was provided, but in spite of said means the stock could swing around and vary its position, and hence vary 40 the grading to some extent, whereas by having the elongated parallel guides and extended table the feeding is compelled to be central over the entire length of each piece 45 of stock. Pivoted to the gate 104 is a link 110 for operating a locking dog 111 normally held down by a spring 112, and operating, when the gate 104 falls, to engage the teeth 113 and thereby lock the locking wheel 31 so as to prevent further transmission 50 of thinness measurement as determined by the feeler mechanism. The oppositely extending teeth 114 of the ratchet wheel 31 are located to be engaged by a pawl 115 pivoted at 116 and normally moved into engaging 55 position by a spring 117 when released by a rod 118 extending from an arm 119 projecting rigidly from a shaft 120 at whose opposite end is a rod 121 on which is adjustably mounted a foot or shoe 122 to be 60 engaged by the forward end of the stock as it is fed through the machine, said engagement with the forward end of the stock serving to rock the shaft 120, raising the rod 118 so as to release the pawl 115 and cause its lower end to engage the teeth 114 of the ratchet wheel 31 and thereafter permit said ratchet wheel to be moved by the transmission lever 22 only in a direction corresponding to successive increments of thinness 65 detected by the feeler mechanism. The

position of said shoe or foot 122 thus determines the given point in the length of the stock from which the feeler mechanism shall begin to be operative. I omit herein an exhaustive explanation of these functions, as 70 said explanation is found fully set forth in my above mentioned patents. A shoe or presser plate 123 co-operates with a feed chain 124 in facilitating the feeding of the stock from the feeler feed rolls to the gage 75 roll and skiving mechanism, being held yieldingly by springs 125 and bolts 126 at its opposite ends. The transmission plate 22 is delicately adjusted by a spring 127 and thumb screw 128 in the end of a bracket 80 129 mounted for convenience on the lower end of the screw 15.

85 Because of the slotted construction 27 and the arrangement of the adjacent parts of the transmission mechanism, it will be seen that as soon as a piece of stock has passed out of engagement with the lower feed roll or feeler device 3, said roll and its connected parts are at once automatically restored by the spring 14 to work-receiving position, but the grade-setting mechanism is maintained set by the ratchet wheel 31 acting as a locking wheel until the work has been grade-marked and skived, whereupon these parts are automatically restored to normal position. 90 In other words, as soon as the stock has been measured or its relative thickness and thinness determined by the feeler mechanism, said feeler mechanism is automatically restored to normal position independently 95 of the grade-marking and skiving mechanisms, which remain set until they in turn have performed their functions. By thus rendering, to a degree, these various mechanisms independent of each other, and subdividing the movements of the machine, the gage roll and the rest of the grading mechanism at the rear end of the machine are relieved of the strain or undue work brought 100 upon them by the mechanism of my former 105 machines, in which the tension spring at the front end of the machine held all the parts under continuous tension from the entrance of the stock into the machine until it left the machine. In my present invention, the 110 corresponding spring 14 is independent of the rest of the mechanism, so far as transmitting thereto any strains is concerned, and the forward portion of said remaining mechanism is not required to remain under 115 strain after the performance of its functions, but is restored to normal position before that portion of said remaining mechanism which is at the rear end of the machine has finished performing its functions. This provision 120 conduces materially to the delicacy and 125 accuracy of grading.

The machine is controlled through fast and loose pulleys 130, 131 on the main shaft 80 from which a train of gears 132, 133, 134, 135

135, 136, 137 positively drives the feed rolls 2, 3, the gears 136, 137 having specially formed long teeth, see Fig. 1, in order to permit of the relative vertical movement of 5 said rolls without interfering with the positive and even driving movement. The under roll 60 is positively driven by a gear 138 in mesh with the gear 132, and the gage roll 42 is driven by a gear 139 in mesh with the 10 gear 79, and the driving chain 124 is driven by a sprocket chain 140 passing over a sprocket wheel 141 on the rear driving shaft 142 of said sprocket chain 124, and over a sprocket wheel 143 on the shaft of the lower 15 roll 60. A further feature of importance resides in providing additional means for materially decreasing the pressure on the stock when it is first put into the machine and for decreasing the resistance of the 20 initial movements of the grading mechanism, said means, although capable of various embodiments, being herein shown as consisting of a bolt 144 held by a check nut 145 adjustable in a cross piece 146 at the rear end of 25 the machine in line with the rear end of the rack bar 34 so that the head 147 of said bolt positively limits the rearward movement of said rack bar, see Fig. 4. By this means, in addition to the other functions just mentioned, 30 the parts of the machine may be set so as to prevent grading below any desired minimum measurement. By screwing the bolt outward or forward the rack bar is prevented from moving sufficiently rearward 35 when the machine is at rest to permit the cam stops or stepped inclines 39, 40, coming in contact, and hence, the latter being out of contact when the stock is put in the machine, the initial starting movement is free and 40 without the drag and tendency to stick or cling to each other which would be the case if said inclines were left in contact with each other.

The operation of the machine has already 45 been quite fully set forth and may be briefly summarized as follows: The gate 104 being in its normal upraised position, the operator inserts the leather piece between the positioning devices or length guides 108 so that 50 its leading end will engage between the rolls 2, 3. This operates to separate the rolls, *i. e.* to lower the feeler roll 3 and thereby permit the lever 22, under the influence of its spring 127, to rotate the ratchet wheel 31 counter-clockwise a distance corresponding with the 55 extent to which the leather piece has thus separated the rolls 2 and 3. The leather piece is fed rearward in the machine by the rolls 2, 3, and as its leading end strikes the trip or foot 122, the latter is raised, and thereby, through the parts 121, 120, 119, 118, 115 and 117, brings the pawl 115 into engagement with the teeth 114 of the ratchet wheel 31 (which, as just pointed out, has 60 already been turned sufficiently therefor by

the entrance of the stock between the rolls 2, 3). As the leather piece now continues to travel rearward between said rolls, if a thicker spot is met with, the rolls separate but without influencing the ratchet wheel 31, 70 inasmuch as the pawl 115 and teeth 114 prevent any movement in this direction, *i. e.* in response to increases in thickness. If, on the other hand, a thin spot is met with, the lever 22 is instantly pulled upwardly by 75 whichever feeler post 17, 18 is vertically beneath said thin spot, and the ratchet wheel 31 is correspondingly rotated clockwise the distance of one or more teeth as required for properly measuring said thin spot. 80 When the leather piece has traveled its length into the machine, thereby permitting the gate 104 to fall, the latter, through the connection 110, causes the pawl 111 to engage the locking teeth 113 of the ratchet wheel 31 85 in opposition to the engagement of the teeth 114 by the pawl 115, so that said ratchet wheel cannot thereafter move in either direction until after the leather piece has been marked. Meanwhile the clockwise turning 90 of the ratchet wheel 31, as it has successively taken up or measured the successive increments of thinness of the leather piece, has correspondingly set the marking mechanism through the train of parts 30, 32, 33, 34, 35, 95 36, 37, 38, 50, 46, and 45. When the leading end of the leather piece reaches the rolls 42, 60, it enters between them and instantly raises the roll 42, thereby, through the parts 93, 92, 89, 88, and 86, disengaging the cam 100 plate 81 from the roll α of the clutch gear 76 whose spring 77 then instantly slides said gear to the left, Fig. 5^a, into driven engagement with the member 78 of the gear 79. This causes the train of gears 76, 75, 74, and 105 73 to rotate, the latter serving to rotate the lifter cam 52 over to the left Fig. 1, thereby releasing the plunger 53 of the head 49, which instantly falls under the influence of the springs 54, and is instantly raised by the 110 engagement of the lifter cam 52 with the lower end of the plunger 53. But in the instant that the head 49 fell, it thereby caused the marking wheel 44 to mark the top side 115 of the leather piece with the grade mark to which said marking wheel had been set. The marker is instantly raised and stopped by its actuating mechanism, including the roll or pin 99 which engages the left hand end of the lever 97, Fig. 5, and thereby 120 raises the overhanging end 95 of the latch 84 out of engagement with the dog 86 so as to permit the spring 82 to swing the cam plate 81 back into engaging relation with the clutch member 76 which cam plate serves 125 to retract the clutch member and stop further movement of the actuating mechanism of the marker. The leather piece now continues on through and out of the machine. As it escapes from beneath the roll 130

42, the latter falls and thereby restores the dog 86 to the position shown in Fig. 5 and also raises the gate 104 to permit another leather piece to be fed into the machine.

5 Having described my invention, what I claim as new and desire to secure by Letters Patent is:—

1. In a machine of the kind described, a feeler mechanism located to operate on the 10 under side of a piece of stock to determine thinnesses therein, and grade-marking mechanism arranged to operate on the upper side of said stock, connections between the aforesaid mechanisms including means rendering 15 the marking mechanism responsive only to the final determination of said feeler mechanism in feeling of a number of different thinnesses.

2. In a machine of the kind described, the 20 combination with detecting mechanism, of grading mechanism responsive thereto for indicating the grade of the leather piece, starting means to set in motion said grading mechanism and mechanism for positively 25 limiting the grading mechanism to one grading movement for one starting operation.

3. In a machine of the kind described, the 30 combination with detecting mechanism, of grading mechanism responsive thereto and including a marker, operating means for said marker, including starting means to set in motion said operating means, and means for positively stopping the marker after it has performed a single marking 35 movement.

4. In a machine of the kind described, the combination with detecting mechanism, to operate on a piece of leather, of a grade-marker and connections responsive to said 40 detecting mechanism, and means for starting the marking movement of said marker, including means adapted to be engaged by the piece of leather and movable thereby.

5. In a machine of the kind described, the 45 combination with detecting mechanism to operate on a piece of leather, of a grade-marker and connections responsive thereto, and means for starting the marking movement of said marker, including means adapted to be engaged by the piece of leather and movable thereby, and connections operated by the movement of said 50 movable means for timing said starting means.

55 6. In a machine of the kind described, the combination with detecting mechanism to detect the thinness of a piece of leather to be grade-marked, of a grade-marker mechanism responsive thereto, and means for 60 starting the marking movement of said marker mechanism, including a roll adapted to be lifted by the piece of leather when the latter is to be marked, and connections operated by the raising of said roll for timing 65 the starting of said starting means.

7. In a machine of the kind described, the combination with detecting mechanism to operate on a leather piece, of a grade-marker responsive thereto, operating means for said marker, including a clutch, means 70 normally restraining said clutch in inoperative position, movable means adapted to be engaged and moved by the leather piece when ready to be marked, and connections from said movable means for moving said restraining means from said restraining position.

8. In a machine of the kind described, the combination with detecting mechanism, of a grade-marker responsive thereto, setting 80 mechanism to set the marker according to the thickness of an article to be marked, operating mechanism for moving said marker down and up, including a stop device, and a trip for said stop device actuated once 85 for each complete operation of said marker.

9. In a machine of the kind described, the combination with detecting mechanism, of a grade-marker responsive thereto, setting 90 mechanism to set the marker according to the thickness of a leather piece to be marked, operating means for said marker, including a clutch, means normally restraining said clutch in inoperative position, movable means adapted to be engaged and moved by the leather piece when in position to be marked, connections from said movable means for moving said restraining means from said restraining position, a movable 95 device carried by said restraining means normally rendering said restraining means operable by said connections, and means actuated by said operating means for moving said movable device to render said restraining means inoperative with relation to said connections.

10. In a machine of the kind described, the combination with detecting mechanism, of a grade-marker responsive thereto, setting 110 mechanism to set the marker according to the thickness of a leather piece to be marked, operating mechanism for said marker, including a spring-impelled clutch, a spring-actuated restraining device for normally holding said clutch inoperative, a gage roll movable by the leather piece being graded, connections from said gage roll to said restraining device for operating the latter in timed relation to the gage roll, means for disconnecting said restraining device from said connections, and means for actuating said disconnecting means in timed relation to the marker.

11. In a machine of the kind described, the combination with detecting mechanism, of a grade-marker responsive thereto, setting mechanism to set the marker according to the thickness of a leather piece to be marked, operating mechanism for said marker, including a spring-impelled clutch, 115 120 125 130

a spring-actuated restraining device for normally holding said clutch inoperative, a gage roll movable by the leather piece being graded, connections from said gage roll to said restraining device for operating the latter in timed relation to the gage roll, a latch normally rendering said restraining device operative by said connections, and means actuated by said operating mechanism for 10 moving said latch from said normal position after each marking movement of the marker.

12. In a machine of the kind described, the combination with detecting mechanism, of a grade-marker responsive thereto, setting mechanism to set the marker according to the thickness of the stock to be marked, operating mechanism for said marker, including a spring-impelled clutch, a spring-actuated restraining device for normally 20 holding said clutch inoperative, a latch mounted on said restraining device, a gage roll adapted to be lifted by the stock being graded, connections from said gage roll to said restraining device, including a dog 25 movable in the path of said latch for actuating the restraining device, and means actuated by said operating mechanism after each marking movement of the marker for disengaging said latch from said dog.

13. In a machine of the kind described, the combination with detecting mechanism, of grading mechanism, governed thereby including a reciprocating marking die, a pinion for raising said die, a clutch for driving said pinion, a cam plate for stopping said clutch, a latch carried by said cam plate, means engaging said latch to hold the 30

35

cam plate in inoperative position, a tripping lever for moving said latch to disengage said engaging means, and means on said pinion for actuating said tripping lever when said die has accomplished one marking movement. 40

14. In a machine of the kind described, the combination with detecting means, of grading mechanism governed thereby, including means having a sudden swinging-movement tending by reason of its momentum to make false moves, transmitting means from said detecting mechanism to 45 said swinging-moving means for giving the latter said sudden movement, and momentum-retarding means arranged to prevent the false moves of said swinging-moving means. 50

15. In a machine of the kind described, the combination with detecting means, of grade-marking mechanism governed thereby, including a rotary marker, an actuator therefor having a sudden arc-movement, setting means to set a marking mechanism in response to said detecting mechanism with said sudden movement, and momentum-retarding means arranged to prevent the false moves of said marking mechanism when being set. 55

In testimony whereof, I have signed my name to this specification, in the presence of two subscribing witnesses.

ELMER P. NICHOLS.
